FILM REEL

Karl Wolfgang Thalhammer, Sunland, Calif.

Original application March 7, 1950, Serial No. 148,153, now Patent No. 2,563,198, dated August 7, 1951. Divided and this application May 28, 1951, Serial No. 228,675

3 Claims. (Cl. 242—74)

1

This invention relates to a reel construction and more particularly to an improved arrangement of reel hub and side members for releasably attaching an end of a strip material, such as motion picture strip film, to a reel for winding thereon. This is a divisional application of my application Serial No. 148,153, filed March 7, 1950, Patent No. 2,563,198 granted August 7, 1951, relating to an improved reel construction.

Prior reel construction for strip film generally comprised two perforated circular discs, irreversibly attached to a central axial hub which spaced the two discs and around which the strip film is wound. Attaching an end of a film to the central hub of prior reels is awkward and inconvenient because of necessity of introduction of an end of the film between the fixed discs and manipulation of the end of the film to attach it to the central hub in a restricted space where movement of fingers is extremely limited. A similar difficulty is encountered when the end of the film is detached from the hub, the restricted space causing manipulation of fingers very awkward and difficult in order to free the end of the film.

This invention contemplates an improved film attaching means wherein the disadvantages of prior proposed film attaching means are avoided and wherein an end of a strip film may be quickly and easily attached to the hub of a reel construction. While the improved arrangement of the reel for attaching film thereto is illustrated on a reel construction of the type shown in the aforesaid application Serial No. 148,153, it is understood that it may be employed upon other reel constructions having virtually flat, non-flanged, separable side members.

An object of the invention is to provide a reel construction with improved means for introducing and securing an end of a film to the reel.

Another object of this invention is to design a reel construction having an improved arrangement of cooperative reel side members and reel hub, whereby one side member is removably coupled to the hub to afford convenient access to a film end attaching means carried by the reel hub.

A further object of this invention is to provide a reel for strip film wherein means are provided for limiting the amount of film insertable into the film end holding means.

Another object of this invention is to provide a reel for strip film wherein the film attaching means is designed for lateral insertion of a film end into a reel hub and wherein the film end

is held by a spring member against the wall of the hub.

Generally speaking, the improved reel construction contemplates at least one side member and a hollow reel hub carrying therewithin novel coupling means whereby the side member may be easily removed to expose a circumferential edge of the hub and may be assembled with the hub in tight contact with said edge. The cylindrical wall of the reel hub is provided with a pair of spaced transverse slots each adapted to receive a film end and having open ends in the exposed edge of the hub facing the removable side member. Over each slot extends a spring member which normally bears against the wall of the hub, beyond the slot, the film end being slidable beneath the spring member and held thereby. Limiting means for longitudinally positioning the end of the film is formed in the reel hub wall in spaced aligned relation to each spring member.

Other objects and advantages of this invention will be readily apparent from the following description of the drawings in which:

Fig. 1 is a sectional view of a reel construction embodying this invention, the reel being disposed in film winding position, the section being taken in a transverse diametrical plane.

Fig. 2 is a fragmentary side view of one side member and reel hub shown in Fig. 1, the view being taken from the plane indicated by the line II—II of Fig. 1.

Fig. 3 is a fragmentary enlarged perspective view of a portion of the circumferential edge of the reel hub employed in Fig. 1 illustrating the improved film holding means.

Fig. 4 is a fragmentary enlarged view of a locking means carried by a side member, the view being taken from a plane indicated by line IV—IV of Fig. 2.

The reel construction shown in Fig. 1 may comprise a flat circular axially ported first side member 10, which may be provided with enlarged spaced openings 11 for observation of progress of the film when being wound or unwound. Centrally disposed on side member 10 is a hollow cylindrical reel face member or reel hub 12 secured to one face of side member 10 by any suitable means, such as spaced rivets 13. The reel hub 12 extends laterally outwardly from side member 10 and comprises a cylindrical outer wall 14 having a width slightly greater than the width of a film to be wound upon the reel, said wall 14 serving to maintain a second side member 15 in proper spaced relationship. The

reel hub 12 may be provided with a concentric inner central boss 16 having an axially ported circular flat face 17 lying in a plane spaced inwardly from the plane defined by the circumferential outer edge of the cylindrical wall 14.

The face 17 of boss 16 carries resilient coupling means for holding side members 10 and 15 in assembled relationship. The coupling means may include a generally circular axially ported member 18 secured to face 17 as by rivets 18a. A plurality of pairs of diametrically opposed radially outwardly and circumferentially extending resilient tabs 19 are provided on the circumferential edge of member 18. Each tab 19 is integrally joined with member 18 at one end, the remaining portion of the tab being normally biased inwardly and out of the plane defined by the circular member 18 as indicated by dotted lines 18b. Each tab 19 is provided with an enlarged port 19a adjacent the end joined to member 18 and with an arcuate slot 19b extending to the opposite inwardly biased end portion of the tab.

The resilient tabs 19 cooperate with double headed buttons 20 carried by a circular axially ported flat wall 21 of the second side member 15 for providing a coupling means for releasably locking the side members 10 and 15 in assembled relationship, side member 15 being capable of reversible attachment thereto by the arrangement of the double headed button 20. Since the resilient tabs 19 are normally biased inwardly, rotation of side member 15, after cooperative engagement of the buttons 20 with tabs 19, will pull member 15 toward side member 10 until the outer surface of wall 21 is firmly seated against the circumferential edge of wall 14 of the reel hub 12.

As best seen in Fig. 4, each button 20 includes an inwardly tapering surface 20a on each head, said tapering surfaces terminating in a shouldered shank for spacing said tapering surfaces outwardly from the wall 21 of the second side member 15. The tapering surfaces facilitate the grasping of the edges of the slot 19b in the resilient tab 19.

When the side member 15 is uncoupled from the hub, the outwardly facing circumferential edge of wall 14 is exposed and convenient access is afforded to the means for connecting and holding an end of a strip film to be wound on the roll as best seen in Fig. 3. The cylindrical wall 14 of the reel face member or reel hub 12 is provided with two spaced parallel slots 22 having open ends at the circumferential edge of wall 14 for facilitating lateral insertion of an end of a film into one of the slots when member 15 is detached. Between slots 22 is provided a clip 23 secured as by a rivet 24 to the intervening portion of wall 14. The clip 23 is provided with oppositely extending resilient fingers 25, each finger being first curved upwardly to extend across a slot 22 in spaced relation thereto for facilitating insertion of a film end. Each finger then curves downwardly and terminates in an upwardly curved end 26 presenting a convex surface normally biased against the inner surface of wall 14. A stop tab 27 is formed in wall 14 spaced from and in alignment with each finger 25 as by punching a rectangular portion of the metal inwardly.

When side member 15 is removed from assembled relationship with side member 10, an end of a strip film to be wound may be laterally inserted through the open end of a slot 22 and

then moved longitudinally beneath the resilient finger 25 until the end edge of the film abuts against the stop tab 27. The configuration of finger 25 facilitates and guides such longitudinal movement. The resilient finger 25 exerts sufficient pressure contact against the end of the film to hold the film during a winding operation. The clip and double slot arrangement affords attachment of an end of a film to the reel for winding in either clockwise or counter-clockwise direction.

After the film end has been secured on the reel hub 12 the side member 15 may be attached to the reel hub and first side member 10 by cooperatively engaging the double headed buttons 20 with the resilient tabs 19 which afford a simple, convenient coupling means.

The advantages of the improved reel construction are readily apparent. The locking buttons described cooperate with the resilient tabs in reverse positions of the side member 15 so that the side member may be quickly and easily attached or removed during a film attaching operation. Further, the coupling means, that is the inwardly biased resilient tabs 19, draw the member 15 into tight contact with the circumferential edge of cylindrical wall 14 and closes the open ended slots 22 of the film attaching means. The end of the film is conveniently and easily attached to the reel when the side member 15 is removed without awkward and cumbersome manipulation of fingers in a restricted space. The end of the film is readily guided and adjusted into proper position by cooperation of resilient fingers 25 and stop tabs 27.

It is understood that all modifications and changes coming within the scope of the appended claims are embraced thereby.

I claim:

1. In a reel for strip film and the like, the combination of: a pair of spaced circular axially ported side members; a centrally disposed reel hub member connecting said side members and including a cylindrical wall, at least one of said side members being detachable from said reel member; and means for attaching an end of a strip film to said reel member including two spaced transverse slots in said cylindrical wall, each of said slots being provided with an open end facing the detachable side member for lateral insertion of a film end portion when the detachable member is removed, a resilient clip each end of which is of ogee configuration secured to the inner surface of the cylindrical wall between said slots, each end of the clip extending upwardly above and across a slot and then downwardly for resilient pressure contact against the inner surface of the wall and adapted to hold said film end portion therebetween, beyond such slot, and an inwardly extending stop tab carried by the wall beyond each end of the clip and in alignment therewith for limiting longitudinal movement of the film end portion.
2. In a reel for strip film and the like, the combination of: a side member; a centrally disposed hollow cylindrical reel face member carried by the side member and extending to one side thereof; a slot in said cylindrical member, said slot having an open end facing away from said side member; a resilient clip of ogee configuration carried by and within the cylindrical member, said clip having an end extending across the slot for contact with the surface of the cylindrical member beyond the slot whereby a film end portion may be positioned in said slot by pas-

sage through said open end and then longitudinally moved between the end of the clip and the surface of the cylindrical member.

3. In a reel construction for strip material comprising a pair of side members held in spaced relation by a cylindrical hollow reel hub member, at least one of said side members being separable from said reel member, the combination of: means for attaching an end of a strip of material to the reel member including a slot in said reel member provided with an open end when the one side member is separated from the reel member for lateral insertion of a film end portion, and resilient means of ogee configuration secured to the inner surface of the reel member 15 and extending across the slot for guiding the end of a strip of material against the inner surface of the reel member, said resilient means being

in resilient contact with the inner surface of the reel member for holding said end at an area spaced from said slot.
